UNITED STATES PATENT OFFICE.

THOMAS H. BRADY, OF NEW BRITAIN, CONNECTICUT.

DESIGN FOR A HANDLE FOR KNIFE-SWITCHES.

41,731.

Specification for Design.

Patented Aug. 29, 1911.

Application filed May 13, 1911. Serial No. 627,052. Term of patent 14 years.

To all whom it may concern:

Be it known that I, THOMAS H. BRADY, a citizen of the United States, residing at New Britain, in the county of Hartford and State of Connecticut, have invented a new, original, and ornamental Design for a Handle for Knife-Switches, of which the following is a specification, reference being had to the accompanying drawing, forming part thereof.

Figure 1 is a front elevation of a handle for knife switches embodying my invention. Fig. 2 is a side view of the same.

I claim:

The ornamental design for handle for knife switches as shown.

THOMAS H. BRADY.

Witnesses:

M. A. SHUCKEROW,
H. E. HART.
